UNITED STATES PATENT OFFICE.

PENELTON G. MCGARRY, OF DALLAS, TEXAS.

WELL-DRILLING BIT.

1,848,133.

Specification of Letters Patent. Patented July 18, 1930.

Application filed February 26, 1928. Serial No. 281,912.

To all whom it may concern:

Be it known that I, PENELTON G. McGARRY, a citizen of the United States, residing at Dallas, in the county of Dallas and State of Texas, have invented certain new and useful Improvements in Well-Drilling Bits, of which the following is a specification.

This invention relates to new and useful improvements in well drilling bits.

10 The invention contemplates the provision of a drilling point which is arranged to operate in advance of the cutting edges of the bit so as to at all times center the bit and make it bore true. One of the features is 15 to make the point removable so that it may be readily sharpened or replaced if necessary and also to make the cutting wings of the bit removable so that they may readily be taken from the head and sharpened or 20 replaced whenever necessary. It is obvious that such arrangement has a great many advantages because the parts are interchangeable and one may be replaced without replacing the entire bit, thus making for economy and a saving in expense.

In carrying out the invention a head is provided and formed with a socket to receive a point which is fastened in the head in a suitable manner. Removable wings are 30 provided with shanks fitting in the head and suitably fastened so as to be removable. The wings are provided with seats for receiving the point in a compact and efficient manner. Other details will be hereinafter 35 pointed out.

The invention will be more readily understood from a reading of the following specification and by reference to the accompanying drawings, in which an example of the 40 invention is shown, and wherein:

Figure 1 is an elevation of a bit constructed in accordance with my improvement, a portion of the bit being illustrated in section to show the shank of one of the wings,

45 Fig. 2 is a vertical sectional view at right angles to Fig. 1,

Fig. 3 is a plan view of the bit,

Fig. 4 is an underside view of the head with the wings and point removed, and

50 Fig. 5 is an underside view of the bit showing the point.

In the drawings the numeral 10 designates a head which is provided at its upper end with a screw-threaded and tapered shank 11.

55 In each side the head has concavities or

sumps 12 extending downwardly from its upper edge. A central upwardly tapered socket 13 extends entirely through the head. A point member 14 has a tapered tenon 15 fitting snugly in the socket 13. The length of the tenon 15 is such as to occupy the entire length of the socket and whereby the point member will project below the head to the proper point. The upper end of the tenon is screw-threaded and receives a nut 16 65 bearing on a washer 17 which rests on the shank 11. The nut 16 is notched to receive a cotter pin 18 passing through the tenon and locking the parts in position as is obvious.

70 Wings 19 are disposed diametrically opposite on each side of the member 14 and form the lower part of the bit. These wings are shouldered and have considerably greater diameter than the head 10 so as to project 75 laterally beyond the same. Each wing has a vertical cutting edge 20 and an inclined cutting edge 21 on its underside. The face 22 of each wing is curved inwardly from the cutting edge so as to have a gradually reducing radius and thus provide clearance for the material cut as the bit rotates. Each wing is in the form of a quadrant, being beveled 80 inward at 23 on each side toward the center of the bit. Each wing has a vertical seat 24 85 which is angular in cross section so as to receive the point member 14 which is substantially square in cross section. The head 10 has vertical water holes or ports 25 leading down through the head to the sumps and discharging downwardly on each side of the member 14 within the angle formed by the beveled sides 23 of opposite wings as will be clear from Fig. 5.

85 Each wing 19 has a shoulder 26 fitting snugly against the bottom of the head 10 and also a wedge shaped shank 27 extending upwardly from the shoulder. The head has sockets 28 on each side of the socket 13 for receiving the shanks 27. The sockets 28 110 are shaped to snugly receive the shanks 27. Each shank has a screw-threaded stud 29 on its upper end passing through a washer 30 which latter rests on the shoulder of the head. Nuts 31 are screwed onto the studs 105 and bear on the washers. These nuts are fastened by cotter pins 32 passing through the studs. It will be seen that the wings 19 and the point member are securely fastened in the head, but may be easily re-

110

moved by removing any one of the cotter pins and unscrewing the nuts on the part which is to be taken out.

The point member 14 has a specially sharpened point 14' which projects below the cutting edge 21, but is shaped so as to have its cutting edge contiguous to the cutting edges 21, but to project below the same. This is accomplished by the manner in which 5 the point is sharpened and shaped. It will be noticed that the entire lower edges as well as the vertical side edges of the bit form a continuous cutting element. A bit of this kind will cut through any kind of material 10 and will not swing out of line. Of course, whenever the point member 14 is sharpened the wings are also sharpened so as to keep the proper relation between the parts. This bit cannot clog up and will be very fast 15 in its work. The point member may be specially treated and may be formed of a particular kind of metal so as to stand the constant cutting and centering action. It is obvious that either wing or the point may 20 be removed whenever desired. The shanks 25 27 firmly secure the wings in the head and the whole structure is as compact and rigid as if it was made in one piece, so far as its operation is concerned.

30 It is pointed out that the seats 24 receive diametrically opposite corners of the point member whereby the parts are more securely united and the point member is braced against twisting and breaking off.

35 What I claim, is:

1. In a drill bit, a head, removable wings depending from the head, and a removable point depending from the head between the wings and projecting below the wings, the 40 wings having continuous cutting edges along their sides and bottoms, contiguous to the point.

2. In a well drilling bit, a head having sockets, diametrically opposite drill wings

having portions fitting in the sockets of the 45 head, and a point member having a portion fitting in one of the sockets of the head and disposed between the wings and centrally of the drill, the point member having a drilling point extending below the cutting edges 50 of the wings, said point member contacting with the wings throughout the length of the latter.

3. In a well drilling bit, a head having a central socket and sockets on each side of the 55 central socket, wings each having an upwardly extending shank fitting in one of the side sockets of the head, means for fastening the shanks of the wings in the head, a point member having its upper portion fitting in the central socket of the head, the wings having seats for receiving the point member which is disposed therein and centrally of the bit, and means for fastening the point member in the head. 60

4. In a well drilling bit, a head having a central socket and sockets on each side of the central socket, wings each having an upwardly extending shank fitting in one of the side sockets of the head, means for fastening the shanks of the wings in the head, a point member having its upper portion fitting in the central socket of the head, the wings having seats for receiving the point member which is disposed therebetween centrally of the bit, and means for fastening the point member in the head, the wings having vertical cutting edges with receding faces and downwardly inclined cutting edges on their undersides contiguous to the 70 vertical cutting edges, the point member having a drilling point projecting below the inclined edges and sharpened with a cutting edge contiguous to the inclined cutting edges of the wings. 75

85 In testimony whereof I affix my signature.

PENELTON G. MIDGETT.
